UNITED STATES PATENT OFFICE.

WILLIAM A. POWELL, OF BAY CITY, MICHIGAN.

VALVE-GRINDING MACHINE.

1,151,966.

Specification of Letters Patent. Patented Aug. 31, 1915.

Application filed January 29, 1915. Serial No. 5,129.

To all whom it may concern:

Be it known that I, WILLIAM A. POWELL, a citizen of the United States of America, residing at Bay City, in the county of Bay 5 and State of Michigan, have invented certain new and useful Improvements in Valve-Grinding Machines; and I do hereby declare the following to be a full, clear, and exact description of the invention, such as 10 will enable others skilled in the art to which it appertains to make and use the same.

This invention relates to a mechanism adapted to be used especially in grinding valves, though it is understood that the 15 mechanism can be used in a variety of other ways for many other purposes.

The object of the invention is to provide a device of this character with many new and useful features of construction and operation which will be disclosed as the description progresses, the novel features of the invention being hereinafter pointed out particularly in the claims appended to the said description.

25 In the drawings: Figure 1 is a side elevation of the machine. Fig. 2 shows in plan the upper portion of the mechanism. Fig. 3 is an enlarged view of the upper part of the mechanism shown in Fig. 1 and looking 30 in the same direction. Figs. 4 and 5 are, respectively, side and plane elevations of an element of the mechanism. Fig. 6 is an edge view of a pulley and the crank-shaft on which it is mounted, forming a part of the 35 mechanism of the device; and Fig. 7 is a view similar to Fig. 2 of a modified form of construction.

Like reference characters refer to like parts throughout the several views of the 40 drawings.

In the embodiment illustrated in the drawings, a carriage 1 is provided which includes in its construction an upright sleeve 2 adapted to receive the lower end of a post 45 3. It will be noted that the carriage is mounted on rollers making it portable, and that the lower end of the post 3 is loosely received in the sleeve 2 enabling the post to be rotated to carry the mechanism supported thereon to different positions. The 50 portability of the carriage and rotation of the post permits the operating part of the mechanism to be carried to practically any desired point.

55 A horizontal bar 4 is located a distance below the upper end of the post 3, its end

adjacent the post being formed with a fork 5 partially surrounding the post. A vertical member 6 is secured to the bar adjacent the post 3 and lies parallel thereto, its upper end carrying a headed element 7 adapted to be received in a slot in the upper end of the post, which is formed as a hollow tube, so that the horizontal bar 4 and any mechanism carried thereby are readily detachable. A brace 8 is used to reinforce and strengthen the connection between bars 4 and 6. At the outer end of bar 4 a hanger 9 is secured, its upper end extending a distance above the bar and a rod 10 lies between 60 and connects the upper end of the hanger with the upper end of the bar 6 heretofore noted. A brace 11 attached to bar 4 and hanger 9 serves to steady the hanger and hold it in position. Adjacent the post 3 an 65 open frame is formed consisting of a bar 12 in the same plane and lying parallel to bar 4 being spaced therefrom but connected at its ends by a cross member 13 and a U-shaped member 14 as shown.

Above the sleeve 2 an electric motor 15 is supported on a bracket 16 connected to the post 3, said motor driving, through the belt 17, a pulley 18 secured to and carried by the crank shaft 19 which is supported in 70 suitable bearings on the bars 4 and 12. Shaft 19 is provided with a crank 20. A bevel gear 21 is mounted on a shaft 22 journaled in the hanger 9 and has a link 23 secured thereto to which one end of a rod 24 75 is secured, the other end thereof being attached to the crank 20. It will be evident that on rotation of the pulley 18 a reciprocating movement will be imparted to the rod 24 and that link 23 will be given a back and 80 forth rotary movement about the axis of shaft 22. Link 23 is provided with a series of openings 25 at different distances from the axis of shaft 22, the end of the rod 24 85 being connected to the link at these openings by any suitable connection. It will be evident that on moving the end of rod 24 toward the shaft 22 gear 21 will be given rotation through a greater arc with each 90 semi-revolution of the pulley 18, than if it is moved farther toward the end of the link 23. In this way the gear 21 may be given a back and forth rotary movement through various arcs of revolution or if the end of the rod 24 is carried inwardly far enough 95 100 the gear 21 may be given a continuous rotation in one direction.

The hanger 9 at its lower end is formed with a stirrup-like support 26 carrying a bevel pinion 27 on a shaft 28 which extends through the support. This pinion meshes 5 with the gear 21 and is driven thereby while shaft 28 connects, by means of the universal joint 29 with a shaft 30 rectangular in cross section inserted in and secured to the tubular sleeve 31 of similar interior cross section 10 which at its lower end slidably receives a rectangular bar 32 terminating at its lower end in any suitable socket 33 adapted to receive any suitable tool such as a valve grinder or the like. A hand hold 34 may be 15 loosely mounted on the shaft 32 at a distance above the socket.

Electric wires 35 forming a part of a circuit, lead from the motor and contain a suitable switch 36 which will be located adjacent 20 the position occupied by the operator in handling the mechanism. It will be evident that on operation of this switch the mechanism may be started in motion and that the reciprocatory movements of rod 24 will serve 25 to rotate shaft 33 a number of revolutions in one direction followed by a similar number of revolutions in the opposite direction except when the end of rod 24 has been moved inwardly sufficient that the gear 22 is rotated 30 continuously in one direction. The universal joint 29 permits the operator to swing the tool carried by the socket 33 to different positions while the slidable connection of the shaft 32 in the sleeve 31 permits the raising 35 and lowering of the tool with respect to the work on which it is engaged.

A modification in structure is illustrated in Fig. 7, the pulley 18 and crank 20 being operated and supported the same as previously described but the crank having attached thereto one end of a short rod 37 which, at its other end, is pivotally connected to a horizontal rod 38 having a rack 39 which meshes with a gear 40 secured to and 45 rotating the shaft 28. Rod 38 is suitably supported in ways 41 and it will be evident that rotation of the pulley 18 causes a reciprocation of this rod and the rotation of the gear 40 in one direction followed by a 50 similar rotation in the opposite direction, the tool carried by the mechanism in this manner being operated substantially the same as in the modification illustrated in Figs. 1 and 3.

Various other modifications in construction 55 may be resorted to without departing from the invention defined in the appended claims and the invention is to be considered as comprising all modifications falling properly within the scope of said claims.

I claim:

1. In combination, a support, a bar positioned horizontally and detachably connect-

ed to the support, a pulley mounted adjacent one end of the bar, a crank connected with the pulley, a gear supported adjacent the opposite end of the bar, connections between the crank and gear to give the gear back and forth rotary movements on rotation of the pulley, means to drive the pulley, 65 and a tool holding means operatively associated with and driven by the gear, substantially as described.

2. In combination, a support, a bar positioned horizontally and detachably connected 75 to the support, a crank-shaft located adjacent the support, a pulley on the crank-shaft, means to drive the pulley, a gear carried at the outer end of the bar, an arm secured to the gear, a rod connected to the arm and to 80 the crank on the crank shaft, mechanism driven by the gear, and means for connecting the rod at any one of a plurality of places on the arm, substantially as described.

3. In combination, a support, a bar positioned horizontally and detachably connected to the support, a second bar spaced from and connected to the horizontal bar at a point adjacent the support, a crank shaft supported by and between the bars, a pulley 85 on the crank shaft, means to drive the pulley, a gear mounted for rotation at the outer end of the horizontal bar, mechanism driven by the gear, and connections between the pulley and gear for giving the gear an oscillatory rotary movement about its axis of rotation.

4. In combination, a support, a bar carried by the support in substantially horizontal position, a hanger carried by the bar, a gear rotatably mounted on the hanger, a pinion carried by the hanger meshing with the gear, a shaft connected to the pinion and at its lower end to a sleeve, a universal joint interposed in the length of the shaft, 100 a rod terminating at its lower end in tool holding means slidably mounted in the sleeve, and means to drive the gear, substantially as described.

5. In combination, a post, a bar having a 110 forked rear end seated against the post, means detachably connecting the bar and post, a hanger supported by the bar adjacent its outer end, a gear and pinion meshing therewith rotatably mounted on the hanger, a shaft provided with tool holding means driven by the pinion, and means to give the gear oscillatory rotary movements, 115 substantially as described.

In testimony whereof I affix my signature 120 in presence of two witnesses.

WILLIAM A. POWELL.
